EXPLOSIVE PROJECTILE

Bert Alford Hopper, Flint, Mich.

Application March 15, 1941, Serial No. 383,623

4 Claims. (Cl. 102—56)

This invention relates generally to the class of ammunition and explosive devices and pertains more particularly to improvements in projectiles.

The primary object of the present invention is to provide an improved projectile of the type designed to explode on impact, wherein a novel means is provided for effecting the explosion of the charge carried thereby in the event that the shell strikes its objective a glancing blow rather than making a direct hit thereon.

Another object of the invention is to provide an improved explosive charge-carrying projectile in which the nose thereof is constructed to have shiftable portions which are normally held in one position and which are shifted rearwardly when the projectile strikes an object to effect the firing of a percussion cap for setting off the charge, such shiftable portions of the nose of the projectile being arranged so that the percussion cap will be fired if the projectile strikes an object head on or only strikes the object with a glancing blow.

Still another object of the invention is to provide in an explosive charge carrying projectile, a shiftable firing tip or nose with novel means for maintaining such shiftable tip or nose portion in a set or advanced position from which it is driven, for the purpose of exploding the charge, when the projectile strikes an object.

The invention will be best understood from a consideration of the following detailed description taken in connection with the accompanying drawing, it being understood, however, that the invention is not to be considered as limited by the specific illustration or description but that such illustration and description constitutes a preferred embodiment of the invention.

In the drawing:

Fig. 1 is a view in longitudinal section of a projectile constructed in accordance with the present invention, showing the shiftable tip or nose portions in normal or set position.

Fig. 2 is a transverse section taken on the line 2—2 of Fig. 1.

Fig. 3 is a longitudinal section on the line 3—3 of Fig. 1.

Fig. 4 is a view in elevation of one of the shiftable portions of the nose of the projectile.

Fig. 5 is a view in elevation of the inner side of the other one of the shiftable portions of the nose of the projectile.

Fig. 6 is a view partly in elevation and partly in section of the nose end of the projectile, showing the manner in which the shiftable portions

are maintained in position while the jacket is being applied.

Referring now more particularly to the drawing, the numeral 1 designates the body portion of the projectile in which is formed an explosive charge receiving chamber 2, containing a charge of powder or other suitable explosive 3. The nose end of the projectile is indicated generally by the numeral 4 and this includes the integral frame-like extension 5 of the upper or forward end of the body 1. This frame-like extension 5 has the longitudinally extending opening 6 therein in the floor 6' of which is formed an axial bore 7 in which is set a percussion cap 8. The bore or passage 7 extends through the top end wall 9 of the chamber 2 and into this chamber, as shown in Fig. 1.

As shown in Fig. 1, the diameter of the projectile is reduced slightly throughout approximately half the length thereof starting substantially midway of the ends of the body portion 1 and continuing to the nose or around the tip portion, this reduction being indicated at 10, whereby there is formed a shoulder 11 around the central part of the body.

The frame-like extension 5 of the forward end of the body has two opposite flat parallel faces 12 which extend slightly beyond the floor 6' toward the rear end of the projectile forming the radial shoulders 13.

The numerals 14 and 15 designate shiftable tip or nose portions, each of which is set against a flat face 12 of the frame-like forward end portion 5 of the projectile. The shiftable portion 14 has upon its longitudinal center upon the inner or flat side thereof, the lug 16 which terminates at its forward and rear ends short of the adjacent ends of the shiftable element 14 of which it forms a part and which is of an overall length slightly less than that of the opening 6 in which it positions. Upon the side of this lug 16 opposite from the shiftable portion or element 14, there is a tongue 17, the forward end of which lies at approximately the transverse center of the lug while the rear end extends beyond the rear end of the lug and terminates in a plane substantially paralleling the rear edge or rear face of the portion 14. The distance between the rear face of the lug 16 and the plane of the rear face of the portion 14 is substantially equal to the distance between the floor 6' and the shoulder 13 with which the rear face of the shiftable portion 14 is opposed. As previously stated, the lug 16 is designed to position in the opening 6 and when in

this position, the finger 17 lies upon the opposite side of the frame 5 from the portion 14 and engages the rear end of the face 12 opposite from the portion 14 and thus acts to lock the shiftable portion 14 in position.

The shiftable element or portion 15 which engages against that face 12 opposite from the face engaged by the shiftable portion 14, is shown in elevation in Fig. 4, and is provided with the lengthwise extending notch or recess 18 which opens through its rear edge, to receive the finger 17. In other words, the shiftable portion 15 straddles and rests upon the finger 17 and cooperates with the shiftable portion 14 to complete the circular cross-sectional form or design of the forward end of the projectile. It will, of course, be understood that while the faces of the portions 14 and 15 which are positioned against the faces 12 of the frame 5 are flat, the opposite or lateral faces of the portions 14 and 15 are circular in form and coact with the circular form of the narrow sides of the frame 5 to complete the complete circle of the projectile.

Each of the faces 12 of the frame-like forward portion of the projectile has a laterally extending lip 19 against which the forward end of the adjacent shiftable portion engages when such shiftable portion is in its normal forwardly extended position.

The forward end of the frame portion 5 is cut square across on the line 20 and is provided with the axial passage 21 which leads into the forward end of the opening 6. In the completed projectile, this forward axial passage 21 has fitted therein a tip pin 22 which carries the pointed tip 23 which rests against the flat forward end surface 20 and completes the bullet-like nose formation of the projectile.

In the forward end of the lug 16 there is an axial threaded passage 24 in which is engaged an assembling pin 25, shown in Fig. 6. This pin is employed only in the assembling of the parts of the projectile and has a head 27 which bears against the surface 20 in the manner hereinafter stated.

At the inner end or rear end of the lug 16 there is fixed a firing pin 28 which extends axially of the projectile beyond the inner end or inner face of the lug so that when the lug is forcibly driven rearwardly, this pin will strike the percussion cap 8 to set off or fire the charge 3.

In the completed projectile there is the jacket 29 which is of a thickness corresponding with the depth of the reduced portion 10 of the projectile body and this jacket is slipped on from the forward end of the projectile until its inner end comes to rest against the shoulder 11, and when in this position, the forward or outer end of the jacket will extend slightly over the curved or rounded nose of the projectile, the jacket being tapered off to conform to the nose curvature. This jacket is sweated onto the body of the projectile so as to be permanently and tightly joined thereto and it functions to maintain the shiftable firing elements 14 in their forward positions. These elements when in their forward positions, will have their rear ends spaced from the shoulders 13, as shown in Fig. 1, while their forward ends will be abutted against the adjacent lips 19.

In assembling the parts of the projectile, the lug and finger 16 and 17 respectively of the shiftable firing element or portion 14 are extended through the opening 6, so as to bring the inner face of the portion 14 against one of the faces

12 of the frame 5. The other shiftable portion 15 is then placed in position over the finger 17. The assembling screw 26 is then extended through the passage 21 and threaded into the bore 24 and is drawn up tight so as to pull the two portions 14 and 15 forwardly and tightly against the lips 19. The jacket 29 is then placed over the forward end of the projectile and moved into its final position, it being sweated on or otherwise suitably constricted or tightened so that it will firmly grip the portions 14 and 15 and maintain them against accidental longitudinal movement. The assembling screw may then be removed and the impact tip or point 23 placed in position with its pin-like inner portion firmly fixed in the passage or opening 21. As previously stated, the firing pin 28 is held in spaced relation with the percussion cap until the projectile strikes nose on against an object or strikes an object with a glancing blow so as to hit either of the shiftable portions and cause them to be driven back with sufficient force to cause the firing pin 28 to discharge the firing cap. This will, of course, set off the main charge 3 and cause the explosion of the shell.

The rear end of the powder chamber 2 is closed by the threaded plug 29 or other suitable means.

It will, of course, be readily understood that the impact pin 22 will have yielding rearward movement in the event that it comes into forcible contact with an object so that it will drive the lug 16 rearwardly and fire the percussion cap 8 so as to set off the charge 3 in the chamber of the projectile.

It will also be understood that the extent of movement of the parts 14 and 15 for the firing of the percussion cap 8, has been greatly exaggerated for the purpose of more clearly setting forth structural details but that in the projectile as constructed for use, the limit of movement of the movable elements 14 and 15 and of the firing pin 28 will be relatively slight.

What is claimed is:

45. 1. An explosive charge carrying projectile, comprising a body formed to provide an explosive charge containing chamber and having a tapered substantially solid nose portion, said tapered nose portion including two oppositely positioned 50 elements coupled together across the width of the nose for longitudinal shifting and having a length greater than the length of the tapered portion and a transverse arcuate dimension of more than one-quarter the circumference of the 55 nose, said elements being designed to maintain a normal forward position, the forward ends of the elements when in said normal position being behind the tip of the projectile nose, means for releasably holding said elements in said normal 60 position, the elements being designed to be forcibly shifted rearwardly upon impact of the nose with an object, and means for setting off the charge within said chamber by and upon the rearward shifting of said elements.
65. 2. An explosive charge carrying projectile, comprising a body having an explosive charge containing chamber and a nose portion, said nose portion comprising a central longitudinally extending fixed part of the body having an opening transversely therethrough and two oppositely disposed parts positioned against the central part, one of said opposite parts having a portion extending transversely through the central part 70 and coupled with the other one of the opposite

parts, the said two opposite parts having a limited longitudinal movement with respect to the central part and being normally positioned at the limit of their forward movement, said opposite parts and the fixed part being exteriorly curved to cooperate in forming the nose, means for yieldingly holding said opposite parts in the said normal position therefor, a firing cap for the charge in said chamber, and a firing pin coupled with said opposite parts and arranged to be driven into forcible contact with the firing cap upon movement of the said opposite parts rearwardly from their normal position.

3. An explosive charge carrying projectile, comprising a body having an explosive charge containing chamber and having a nose portion, said nose portion comprising a central longitudinally extending part and two oppositely disposed shiftable parts having contact with opposite faces of the said central part, said central part having a longitudinally extending opening formed transversely therethrough, one of said shiftable parts having a lug disposed in said opening and a tongue arranged upon the opposite side of the central part from the said one part, the other one of said parts being coupled with said tongue, said shiftable parts having a normal forward position with respect to the central part, a firing cap for said explosive containing chamber, a firing pin carried by said lug and spaced from the cap when the said shiftable parts are in their normal forward position, and a jacket encircling the body and maintaining said shiftable parts yieldingly in their normal

forward position, said shiftable parts having rounded outer end portions forming a part of the nose of the projectile.

4. An explosive charge carrying projectile, comprising a body having an explosive charge containing chamber and having a nose portion, said nose portion comprising a central longitudinally extending part and two oppositely disposed shiftable parts having contact with opposite faces of the said central part, said central part having a longitudinally extending opening formed transversely therethrough, one of said shiftable parts having a lug disposed in said opening and a tongue arranged upon the opposite side of the central part from the said one part, the other one of said parts being coupled with said tongue, said shiftable parts having a normal forward position with respect to the central part, a firing cap for said explosive containing chamber, a firing pin carried by said lug and spaced from the cap when the said shiftable parts are in their normal forward position, and a jacket encircling the body and maintaining said shiftable parts yieldingly in their normal forward position, said shiftable parts having rounded outer end portions forming a part of the nose of the projectile, and a pin yieldingly maintained axially in the forward end of the nose and engaging at its inner end with the forward end of the lug, and a tip forming a portion of said last pin and constituting the point of the nose.

BERT ALFORD HOPPER.
